UNITED STATES PATENT OFFICE.

GEORGE B. FREEMAN, OF RACINE, WISCONSIN.

CRANK-PLATE FOR BOLSTER-SPRINGS.

SPECIFICATION forming part of Letters Patent No. 760,977, dated May 24, 1904.

Application filed June 9, 1902. Serial No. 110,727. (No model.)

To all whom it may concern:

Be it known that I, GEORGE B. FREEMAN, a citizen of the United States, and a resident of Racine, in the county of Racine and State of Wisconsin, have invented certain new and useful Improvements in Crank-Plates for Bolster-Springs; and I do hereby declare that the following is a full, clear, and exact description thereof.

10 My invention relates to crank-plates for bolster-springs; and it consists in certain peculiarities of construction and combination of parts, as will be fully set forth hereinafter in connection with the accompanying drawings and subsequently claimed.

In the said drawings, Figure 1 is an under side plan view of my improved device. Fig. 2 is a longitudinal vertical sectional view of the same, taken on the plane indicated by the line 20 2 2 in Fig. 1; and Fig. 3 is a transverse vertical sectional view of the same, taken on the plane indicated by the line 3 3 of Fig. 1.

My invention is an improvement on the device shown in the patent granted October 23, 25 1883, to John Smith, numbered 287,335, and is designed to obviate the defects of the same while retaining all the valuable features, and to that end my device is so constructed as to avoid the objection of weakness and the liability to the accumulation of dust and foreign 30 substances, which impaired the usefulness of the Smith device.

Referring to the drawings, *a* represents my crank-plate, which is substantially flat on both 35 its under and upper surfaces, except that it is formed on its upper surface with the transverse integral hollow socket *b*, open at each end, and there strengthened by the semicircular exterior end flanges *c c*, the plate having an opening *d* on the under side communicating with the interior of the said socket *b*, for the purposes hereinafter set forth. This 40 socket *b* is adjacent to one end of the plate *a*, and the latter, beyond this point, is bifurcated, 45 as shown, to form a pair of fingers *e e*, which are designed to embrace between them one of the ordinary bolster-standards in the ordinary

manner, while on the opposite side of the socket *b* the plate *a* is provided with a perforation *f* to afford a convenient means of securing the plate to the bolster, it being understood that in practice a pair of these plates are employed, one at each end of the bolster. The plate just described is formed of one piece of metal, preferably malleable iron. The 55 crank is shown at *g* and is a double crank, the opposite ends *h h* of which are adapted to receive the ends of the bolster-springs of any ordinary construction, as is well known in the art. 60

The described socket *b*, being wholly closed except at the ends, excludes dust, dirt, and the like, as well as rain, snow, and moisture, and is very strong and durable, affording a complete bearing for the central portion of the crank *g*, the same being bent at one end only and inserted through the socket while in a red-hot condition, and then the other end of the crank is properly bent, a suitable stay or stop being passed through the opening *d* 70 in the plate *a* and held against the crank during this operation, so that while the end of the crank is being bent the central portion is prevented from being forced out of line, and by being thus kept straight all danger of 75 binding or excessive frictional contact of the crank within the socket in after use is obviated.

Having thus described my invention, what I claim as new, and desire to secure by Letters 80 Patent, is—

1. A crank-plate for bolster-springs, comprising a substantially flat plate formed with an integral transverse open-ended socket on the upper surface thereof, the said plate having an opening through its under side communicating with the bore of the socket, the latter being otherwise entirely closed, in combination with a double crank whose central portion is rotatable within said socket. 85 90

2. A crank-plate for bolster-springs, comprising a flat plate formed with an integral open-ended substantially cylindrical socket on the upper surface thereof, the said plate

being bifurcated at one end to form fingers, and having a bevel walled opening through its under side, in line with the space between said fingers, and communicating with the center of said socket.

5 In testimony that I claim the foregoing I have hereunto set my hand, at Milwaukee, in

the county of Milwaukee and State of Wisconsin, in the presence of two witnesses.

GEORGE B. FREEMAN.
